UNITED STATES PATENT OFFICE.

SIDNEY A. BEYLAND, OF ELYRIA, OHIO, ASSIGNOR TO THE DEAN ELECTRIC COMPANY, OF ELYRIA, OHIO, A CORPORATION OF OHIO.

LAMP-JACK FOR TELEPHONE-SWITCHBOARDS.

No. 810,367.

Specification of Letters Patent

Patented Jan. 16, 1906.

Application filed November 25, 1904. Serial No. 234,293.

To all whom it may concern:

Be it known that I, SIDNEY A. BEYLAND, a citizen of the United States, residing at Elyria, in the county of Lorain and State of Ohio, have invented certain new and useful Improvements in Lamp-Jacks for Telephone-Switchboards, of which the following is a specification, reference being had therein to the accompanying drawings.

10 My invention relates to switchboard apparatus for use in telephone-exchanges, and particularly to the signaling apparatus mounted thereon.

15 Specifically stated, it comprises improvements in the mountings and holders for incandescent lamps employed as signals, and has for its object the improvement of such mountings and holders in various particulars that will be hereinafter pointed out.

20 In telephone-switchboards employing incandescent lamps as signals sockets or holders have been provided permitting the convenient insertion and withdrawal of the lamps and for their support in position, so that the lighting of any one lamp would not result in illuminating the numbers or jewels of others. In most cases the sockets have been combined into extended strips, usually 25 accommodating ten lamps each, each strip being provided with means to secure it in position in juxtaposition with a strip containing the line-jacks of the lines to whose calls the lamps respond. Such strips ordinarily comprise two main longitudinal members and

30 two transverse end members, the front longitudinal member being drilled with holes to receive the transparent or translucent windows or jewels and to permit the lamps to be passed into the jacks, while the rear member 35 supports the contact-springs and, if the member itself be of metal, the insulation necessary to prevent short-circuiting. As a means for preventing the cross-illumination referred to the lamps have been jacketed and various

40 other devices have been resorted to, most of which add to the number of parts in the strip and are otherwise objectionable. Moreover, the sockets in ordinary use are not capable of employment interchangeably in positions 45 other than those for which they were specifically designed, and consequently it is necessary to have a complete set of tools and designs of sockets and parts for every different

situation on the switchboard, such as the operator's table and the like.

55 It is the object of my invention particularly to reduce all lamp-sockets to be employed on a switchboard to one standard form, which by simple means may be applied wherever required.

60 A further object is to provide a socket which in itself will prevent cross-illumination, will obviate all danger of injury from heating by a continued illumination of a lamp or of all the lamps, which will provide a perfectly stiff frame without a back strip, and which will remove all danger of accidental short-circuit.

65 My invention is illustrated in the accompanying drawings, wherein—

70 Figure 1 is a plan view of a row or strip of lamp-sockets, commonly called "lamp-jacks." Fig. 1^a is a detail. Fig. 2 is a cross-section taken on the axis of one jack as indicated in dotted lines on Fig. 1. Fig. 3 is a 75 top plan view of a modified form of supporting means for a pair of jacks when used for supervisory lamps on the operator's table or key-shelf. Fig. 4 is a sectional view of the same on the line y y of Fig. 3, and Figs. 5, 6, 80 and 7 show modifications.

75 Referring to the drawings, and particularly Figs. 1 and 2, J J are lamp sockets or jacks arranged ten in a row for use in the face of a switchboard as line-signal jacks. This strip of jacks corresponds in design and dimensions to the line-connection jacks employed in the same switchboard. Each jack is tubular in form, being preferably formed up out of sheet metal of sufficient length to 85 receive the bulb of a lamp L, with its forward end j entirely closed, forming a true tube, and its rear end j' cut away upon one side to form a channeled extension, having two holes j² for the reception of screws or rivets for the 90 springs. I preferably form this rear end by means of special tools, so that the sides and edges are straight, and the channel is square in cross-section, as indicated in the detail Fig. 1^a. Within this squared extension of the jack-tube the contact-springs, with their separating-strips of insulation, are laid, the turned-up sides of the channel j³ preventing 95 their turning or displacement and also keeping the lamp in alignment without the necessity for its bulb coming into contact with 100

the closed tubular portion of the jack. This is a matter of some importance, as it permits ventilation around the lamp-bulb. The jacks are combined into a strip by means of a front plate or bar A of metal in which the ends of the tubes j are secured in any suitable manner, as by being screwed in, by means of riveting, and the like. Each end of the bar A is provided with a transverse slide member a , which may be formed integral with the bar A by casting or may be secured thereto by screws, as shown in Fig. 1. In piling up the jack-strips in the switchboard-panels these end members a come into position to be secured to the stiles in the same manner as the corresponding parts of the line-jack strips. The principal point to be noted in this connection is that all support is from the front and all connecting parts are of solid metal, thereby insuring stability under all conditions and uniformity in the parts as they come from the factory. Within each jack-tube I employ a continuous lining of thin fiber in sheet form—say one thirty-second of an inch thick. This is shown in the figures at j^4 and extends forwardly within the inclosed portion of the tube to the point j^5 , the rear portion of the lamp-bulb upon which the contact-springs s are placed being thus surrounded and any accidental contact to form a short circuit through the jack metal prevented. Inserted in the front end of each tube through the corresponding opening in the bar A is a thimble T, shouldered on the inside with a disk of paper or other material inclosed between and protected by corresponding disks of glass resting on the shoulder and held in place by the spring clamping-ring t' . The transparent members are indicated at t . The thimble, with its window, may be pulled out of the tubes from the front, and the lamps are inserted from the front, the extremity of each lamp-bulb lying within the extension of its thimble, so as to approach quite nearly to the window to increase the intensity of the illumination. Within the rear squared portion or channel of each jack are the contact-springs j^6 and j^7 , each having two holes registering with the holes j^2 in the bottom of the channel and secured in place by the screws j^8 , which are bushed where they pass through the springs and which take into a double washer or clamp of metal j^9 , which is insulated from the upper spring by an interposed rubber washer of the same shape. Each lamp L is provided with a wooden base l , to which it is secured by the metal side springs or strips s , to which the terminals of the filament are connected through suitable leading-in wires. As the lamp is inserted in the jack the base passes between the springs j^6 j^7 , and circuit to the filament is then completed, while the lamp is prevented from turning by the comparatively broad flat surfaces in contact and

by the arrangement particularly whereby the lower spring j^7 rests in the channel and forms a solid support on one side.

In Figs. 3 and 4 I have shown my invention applied to an operator's key-shelf for supporting supervisory lamps. Here, instead of the bar A, I employ a metal piece A', formed in figure-8 shape and secured upon the top of the shelf by a central screw a^2 . This plate is covered by another plate of like shape held in position by a pair of spring-pins passing down into openings a^4 in the plate A'. This second plate is marked A² in Fig. 3 and carries the two jewels or bull's-eyes a^3 , each of which is provided with a spider-guard a' . The plate itself is provided with a wire bail a^6 intermediate of the jewels for the purpose of inserting a suitable tool to remove the plate and jewels when it is desired to have access to the jacks. These jacks are substantially the same in their method of connection to the plate A' as the jacks J of Figs. 1 and 2. Each has its lining of insulating material. Each incloses the bulb of the lamp so far as the illuminated area is concerned, and each has its contact-springs secured and operating in the same manner.

In Fig. 7 I have shown a modification of the jack-tube shown in Fig. 4, whereby each tube may be made independently and secured without reference to the other. The ear a^7 rests against the under part of the operator's table, to which it is secured by a screw. I have shown the jewel a^3 somewhat larger than in the other figure and carried in an open-ended thimble, with a suitable protecting-cage over it. This same construction of bull's-eye or jewel is intended to be used with the jacks of Fig. 1; but the preferred form for line-lamps is that shown in Figs. 5 and 6. On the face of the front strip an escutcheon-plate H is pivoted on a screw h . This plate is provided with openings h' , each of which in normal position registers with a jack, each escutcheon-plate thus providing for a pair of jacks. Each plate on its back has its upper and lower edges turned over or channeled out to form a T slot or slide standing toward the center from opposite ends, and into the two ends of this slot the number-cards t are inserted with or without over and underlying transparent protecting-slips. Obviously the plate H can be made to cover the ends of more than two jacks; but the preferred form is as shown in Fig. 6, the turning of the plate on the pivot uncovering the openings of the jacks in the simplest and least troublesome way. I consider this a rather important feature of the invention and shall therefore claim the construction of Figs. 5 and 6 broadly and specifically.

Having thus described my invention, what I claim, and desire to secure by Letters Patent, is—

1. A lamp-jack for telephone-switchboards formed of one piece of metal, having its front end inclosed in tubular form for a sufficient space to inclose the bulb of an incandescent lamp, and having its rear end extended and formed into a straight-sided channel, with contact-springs and interposed insulation fitted to and rigidly held within said channel, substantially as described. 45
- 5 2. A lamp-jack for telephone-switchboards formed from a single piece of metal comprising a tubular inclosing front portion, and an extended rear portion formed into a straight-sided channel, said tube and channel being 50 lined with insulating material, substantially as described.
- 10 3. A lamp-jack strip for telephone-switchboards comprising a front bar or support of metal having a series of openings distributed 55 along its length, transverse terminal securing members for said bar, and a series of metal jack-tubes having their front ends secured in the openings in the bar and their rear ends extended to receive and support contact-springs, substantially as described.
- 15 4. A lamp-jack strip for telephone-switchboards comprising a front bar or support of metal having a series of openings distributed along its length, transverse terminal securing 60 members for said bar, and a series of metal jack-tubes having the front ends secured in the openings in the bar and their rear ends extended to receive and support contact-springs, together with insulating-linings for 65 said tubes extending between the jack-contacts and the sides of the tube, and between the lamp-contacts and the same when a lamp is inserted, substantially as described.
- 20 5. A lamp-strip for telephone-switchboards comprising a metal front bar or support, 70
